C. J. ERICKSON

SWITCHBOARD SIGNAL

Filed Oct. 27, 1924

Fig. 1

UNITED STATES PATENT OFFICE.

CHARLES J. ERICKSON, OF CHICAGO, ILLINOIS, ASSIGNOR, BY MESNE ASSIGNMENTS, TO AMERICAN ELECTRIC COMPANY, INC., OF CHICAGO, ILLINOIS, A CORPORATION OF MAINE.

SWITCHBOARD SIGNAL.

Application filed October 27, 1924. Serial No. 745,978.

This invention relates in general to switchboard signals.

More specifically it relates to improved means for operating and controlling a 5 switchboard signal of the double supervisory type in which the signals are first displayed by a subscriber and are then restored by the operation of the operator's ringing or listening key.

10 The object of my invention is to provide improved signals of the above character and also to provide improved controlling means therefor which are of simple construction, so as to be readily manufactured and so 15 mounted as to provide ease and accuracy of operation and to prevent their getting out of adjustment in use.

Other features of improvement and further advantages will be pointed out in the 20 following detailed description and claims, reference being had to the accompanying drawings in which—

Fig. 1 is an assembly view of the key shelf escutcheon, showing the ringing and 25 listening key, the back ringing key, and the visual signals.

Fig. 2 is a partial section of the visual signals, drawn as seen from the back of the signals as shown in Fig. 1.

30 Fig. 3 is a top view showing the windowed guard and the visual signal.

Fig. 4 is a detailed drawing of the lever or connecting link which extends between the restoring key and the signals which it 35 controls.

Referring to Fig. 1 in more detail, the escutcheon 1 is arranged to fit into the switchboard key shelf. Rigidly attached to this escutcheon are the magnet mounting 40 brackets 2, the key bodies 3 and 4, and the bushing 5 which forms a bearing for the pin 18 of the restoring lever 14. This restoring lever 14, which is an essential part of this invention, extends along the under 45 side of the escutcheon and is rotated under the control of key 4 to restore the signals 13 to their normal position. This drawing shows the left hand signal 13 in an operated position and the right hand signal in 50 its normal position. It will be noted that the former signal has rotated in a clockwise direction about its bearing pin 29 coming to rest in such a position that the ball 12 of the signal 13 has closed the springs 31.

This ball 12 is also resting against the projection 15 of the restoring lever 14 for a purpose which will be hereinafter explained. The signal or shutter 13 consists of a hemispherical member which is at all times visible through the windows of the cover plate 30. This shutter is made in two distinctive colors, one, usually black, which is visible when the signal is in the normal position, harmonizes with its surroundings and does not attract attention, the other, visible when 55 the signal is operated, contrasts with its surroundings and attracts attention.

It will be understood that the keys 3 and 4 and the magnets 6 and 7 are incorporated in the operator's cord circuit of any well known manual system. The key 3 is operated by moving its lever to the right to establish the so-called ring-back circuit. The operation of this key does not operate the restoring lever and is therefore not an essential 60 part of this invention. Key 4 is a combined ringing and listening key. When it is operated to the right, it closes a ringing circuit. When operated to the left, it locks in 65 operated position and closes the listening circuit. When operated to the left the key 4 also operates the restoring lever 14 to restore the signals which are in operated position.

Fig. 2 which is a partial section of the signal is drawn in the reverse of Fig. 1 so that 70 more detail may be shown. The view is taken at the completion of the restoring operation, with lever 14 in the position occupied at the completion of its rotation. Like 75 parts bear similar reference numerals in the two figures. The shutters of the signals 13 are sectioned to show the balls 12 which are within, and the bearings 29 about which the shutters rotate. The ball 12 forms a weight 80 which rotates the shutter to its operated position after it has been started by the operation of armature 20, and also furnish a surface against which the projection 15 of the restoring lever 14 operates to restore the 85 signal. The armature 20 contains the latch 90 32 and the projection 16, the projection being bent up and back so that it will engage the lever 11 of the shutter 13. The armature in its normal position rests against the 95 backstop 33 which is included as a part of the spring assembly 31.

Fig. 3 is a top view of one end of the

escutcheon, showing one of the signals. The hemispherical guard 30 contains two windows, covered by the celluloid 36 through which the signal shutter 13 is visible. This celluloid is hemispherical and covers the entire under surface of the guard 30.

Fig. 4 is a detailed drawing of the restoring lever shown in the position which it occupies in the assembly drawing Fig. 1.

- 10 The pins 18 which form a bearing about which the lever is rotated are shown at opposite ends of the figure. The pin at the left hand end of the figure fits into the magnet mounting bracket 2 of Fig. 1 and 15 the pin at the right of the figure fits into the bearing in the bushing 5 of Fig. 1. The shoulder 35 rests against the screw 34 which is shown in both Figs. 1 and 2, to lock the lever into the assembly. Projections 15 are 20 the signal restoring projections and 17 is a projection which engages the cam 19 of the restoring key 4.

It will be understood that the signals 6 and 25 7 are operated by the subscriber to re-signal the operator after his connection has been completed. When the subscriber energizes the magnet 7 of the signal the armature 20 is pulled down so that the latch 32 is depressed below the lower point of the lever 11, thus leaving the signal free to rotate in 30 a clockwise direction. The operation of the armature 20 also causes the armature projection 16 to press down upon the wedge-shaped portion of the signal lever 11 in such 35 a manner that the lever is pushed to the left, Fig. 1, and the signal definitely started to its operated position.

The operator upon seeing the signal throws her listening key to the left to listen 40 on the cord circuit. When the key 4 is thrown to the left the cam 19 moves up and engages the projection 17 of the signal restoring lever 14 and rotates the lever around its bearing pins 18. This rotation moves the 45 projection 15 in an upward direction and raises the ball 12 of the signal 13 thereby causing the signal to rotate in a counter-clockwise direction about its bearing pin 29, as seen in Fig. 1. The lever 11 moves 50 down against the latch 32. The lower end of the lever 11 is wedge-shaped so that as the lever continues to travel to its normal position the latch 32 is moved downward against the tension of spring 21. Shortly 55 before the lever 14 completes its rotary movement the latch 32 springs up in back of the lever 11, in which position it holds the signal at normal.

Having described my invention, what I 60 consider new and desire to have protected by Letters Patent will be pointed out in the appended claims.

What is claimed is:

- 65 1. In a telephone switchboard signal, an operator's key, electromagnets with arma-

tures adapted to be attracted thereby, signals adapted to occupy either a displayed or a concealed position, means carried by such armatures for normally holding the associated signal in a concealed position, and means rotated by said operator's key for moving said signals from a displayed to a concealed position. 75

2. In a telephone switchboard signal, an operator's key, vertically disposed electromagnets with armatures adapted to be attracted thereby, signals adapted to occupy either a displayed or a concealed position, means carried by such armatures for normally holding the associated signal in a concealed position, and a lever rotated by said operator's key in a plane at right angles to the plane of rotation of said key for moving 80 said signals from a displayed to a concealed position.

3. In a telephone switchboard signal, an operator's key, vertically disposed electromagnets with horizontally disposed armatures adapted to be attracted thereby, signals adapted to occupy either a displayed or a concealed position, means carried by such armatures for normally holding the associated signals in a concealed position, and means rotated by said operator's key in a plane at right angles to the plane of rotation of said key for moving 85 said signal from a concealed position. 90

4. In a telephone switchboard signal, an operator's key, electromagnets with armatures adapted to be attracted thereby, signals each consisting of a shutter adapted to occupy either a displayed or a concealed position, means carried by said shutters for engaging such armatures when the shutters are in a concealed position, and means comprising a horizontal bar pivoted at points adjacent a shutter and said key respectively rotated by said operator's key for moving 100 said shutters from a displayed to a concealed position. 105

5. In a telephone switchboard signal, an operator's key, electromagnets with armatures adapted to be attracted thereby, signals 115 adapted to occupy either a displayed or a concealed position, means carried by such armatures for normally holding the associated signal in a concealed position, a member having portions engaging said key and said signals, said key being operable to raise the portion of the member engaging it to rotate the member and also raise the portions engaging the signals to restore said signals to a concealed position. 120

6. In a telephone switchboard signal, a shutter, an electromagnet with an armature located between the shutter and the magnet and attracted thereby, said shutter arranged to occupy either a displayed or a concealed 125 130

position and having a projection arranged to engage said armature, and two projections on said armature, one projection on said armature engaging one side of said projection on the shutter to hold said shutter in its concealed position, the other projection of said armature engaging the opposite side of said projection of the shutter as the armature moves to its operated position to definitely 10 start the shutter to its displayed position.

7. In a telephone switchboard signal of the enclosed type, an operator's key, a plurality of signals, each with a concealed and a displayed position, extensions on said signals having their free ends formed into a double incline, electromagnets with armatures with latch mechanism arranged to engage and ride over the apex of the incline of the extensions to hold the associated signals 15 in their concealed position when normal and to start the signals to their displayed position by forcing the extension over the apex of the incline when energized, and means rotated by said key for restoring the signals 20 to their normal positions.

8. In a telephone switchboard supervisory signal, a rotatable hemispherical shutter comprising two sections, a hemispherical cover guard containing windows, a latch, a lever projecting from said shutter at right angles to its axis and terminating in a wedge-shaped portion arranged to engage said latch, means for releasing said latch and rotating said shutter about a horizontal axis 30 to expose one of its sections through said windows, a weight within said shutter arranged to assist said rotation, and means for rotating said shutter in the opposite direction to expose the other said section and to 35 bring said lever into engagement with said latch.

9. In a telephone switchboard supervisory signal, a rotatable shutter, a lever projecting

at right angles from the axis of the shutter and terminating in a wedge-shaped portion, 45 a magnet having an armature, a projection on said armature which engages a surface of said wedge to move the shutter when the magnet is energized, another projection on the armature, means for moving the lever past said other projection and into contact with the first projection, said other projection holding the shutter in its last mentioned position.

10. In a telephone switchboard, the combination of an operator's key and supervisory signals, said signals consisting of shutters arranged to rotate about an axis from a normal to an operated position, a lever projecting from each shutter at right 50 angles to said axis, a ball attached within each of said shutters, a lever having projections arranged to engage said balls, and another projection arranged to engage said key, said lever being pivoted at each end and 55 arranged to rotate about its longitudinal axis under the control of said key to restore said signals to their normal positions.

11. In a telephone switchboard device, a signal having a concealed and a displayed 60 position, an extension on the signal having its free end formed into a double incline, and a magnet, for controlling said signal, having an armature provided with two projections, one of which rides one side of said double 65 incline of said extension and which engages said extension to hold the signal in its concealed position; the other projection engaging the opposite side of said double incline of said extension to definitely start the signal 70 to its displayed position when said armature is attracted by the magnet.

In witness whereof, I hereunto subscribe my name this 23d day of October, A. D., 1924.

CHARLES J. ERICKSON.
